UNITED STATES PATENT OFFICE.

GLENN MORE, OF JAMESTOWN, NEW YORK, ASSIGNOR TO BLACKSTONE MANUFACTURING COMPANY, OF JAMESTOWN, NEW YORK, A CORPORATION OF NEW YORK.

AGITATOR.

1,412,255.

Specification of Letters Patent. Patented Apr. 11, 1922.

Application filed February 7, 1921. Serial No. 443,214.

To all whom it may concern:

Be it known that I, GLENN MORE, a citizen of the United States, residing at Jamestown, in the county of Chautauqua and State of New York, have invented certain new and useful Improvements in Agitators, of which the following is a specification, reference being had to the accompanying drawings, and to the reference characters marked thereon, which form a part of this specification.

This invention relates to improvements in agitators.

Agitators heretofore used in the tubs of washing machines have usually been made of wood, and comprise a relatively thick disc with depending prongs or fingers. The latter frequently become loose, and if the disc is not relatively thick and heavy, it readily cracks and splits and becomes damaged. This thickness and heaviness is objectionable in an agitator for it occupies too much of the space in the wash tub.

The principal object of my invention, therefore, is to construct an agitator or dolly adapted for use in tubs of washing machines and which will be made of metal and so constructed as to occupy the minimum of space, combined with the maximum of efficiency, and which will be cheap to manufacture.

In that form of the invention illustrated in the accompanying drawings:

Fig. 1 is a side view of a portion of a washing machine, equipped with my improved agitator.

Fig. 2 is a top plan view of the agitator on an enlarged scale.

Fig. 3 is a vertical, sectional view of the agitator, taken in the plane of the dotted line 3—3 of Fig. 2.

Fig. 4 is a horizontal sectional view taken in the plane of the line 4—4 of Fig. 3, and looking in the direction indicated by the arrows.

Fig. 5 is a horizontal sectional view taken in the plane of the line 5—5 of Fig. 3, and looking in the direction indicated by the arrows.

Fig. 6 is a perspective view of the shaft connecting member.

Fig. 7 is a perspective view showing the inside and the outside of the removable bearing blocks.

Referring now to the drawings, A represents a washing machine tub in which is

mounted an operating shaft B with suitable shaft operating mechanism indicated at C, whereby the shaft B is given a rotary, reciprocal motion about its vertical axis in the manner familiar to the trade, and which need not be further described in this application. To the lower end of this shaft B is attached the agitator designated as a whole by the letter D. The agitator D comprises the dolly member E, as a whole, the collar member F as a whole, a pair of removable bearing blocks G, as a whole, and a shaft attaching member H.

The shaft attaching member H is of peculiar formation. At its upper end it is provided with a cylindrical portion 1, suitably recessed as indicated by dotted lines 2, of Fig. 6, to receive the lower end of the shaft B, to which it is attached or secured by the pin 3 or other suitable and convenient means. Below the cylindrical portion 1 is a web 4 terminating in a circular or disc shaped head 5. Extending upwardly from the head 5 to near the upper end of the cylindrical portion 1, are longitudinally arranged guide members 6, so that the member H appears to have diametrically opposite circular wings 6 for the purpose hereinafter set forth.

The dolly E is substantially square in outline, in the form illustrated, each side margin being concave and each side terminating in rounded corners. Centrally of the top of the dolly E is a collar member F, comprising a circular cap shaped part or hood 8, provided with radial flanges 9, by which the collar member F may be secured to the dolly E by means of bolts 10. The top of the collar F is provided with an aperture which affords a shoulder 11 against which the shoulders 12 of the removable bearing blocks G will bear, when the bearing blocks are in proper position. The surfaces 12 and 11 are shown bearing against each other in Fig. 3, and are also indicated by dotted lines in Fig. 2. The shape of this opening or aperture in the top of the collar F will conform to the exterior contour of the bearing blocks G, as will be readily understood.

The interior contour of the bearing blocks G will be such as to afford a sliding bearing for the wing flanges 6, 6, and the cylindrical or barrel portion 1 of the shaft attaching member H. To this end, each of the bearing blocks G are provided interiorly with

three longitudinally arranged concave surfaces 13, 14, the concave portion 13 being centrally arranged as shown in Fig. 7. At the bottom of each of the blocks, the outwardly directed flange 12 is suitably recessed, centrally, to provide oppositely facing shoulders 15, 15, adapted for engagement with shoulders 16, 16, on the interior ribs 17 with which the collar member F is provided. When the bearing blocks G are placed within the collar F the contact of the shoulders 15, 15, with the shoulders 16, 16, prevents any lateral displacement of the parts. The radius on which the recesses 13, 18, are drawn, is such as to make the diameter of the opening formed by the two recesses 13, 13, somewhat less than the diameter of the button or disc 5, thus affording a shoulder or surface against which the upper part of the button 5 may engage, which will limit the relative movement between the member H and the member D in one direction. This shoulder is indicated in dotted lines at 18 in Fig. 5.

The interior faces of the ribs 17 will bear against the exterior surfaces 19 of the flanges 12 of the bearing blocks G. The dolly E is provided with a central aperture surrounded, above the top 7, with a pair of diametrically opposed semi-circular walls 20, the ends 21 of which bear against the shoulders 16, 16, of the ribs 17 of the collar F, as clearly shown in Fig. 4. The two bearing blocks G rest upon the upper margin or edge of the walls 20, as clearly shown in Fig. 3. Thus when the bearing blocks G have been placed about the member H and the two have been placed through the aperture in the collar F, being inserted from the under side of the collar, and then these three parts placed over the dolly E, until the bearing blocks G rest upon the top of the two walls 20, 20, the proper position of the parts will be readily determined, because the walls 20, 20 will register in the proper spaces between the ribs 17, 17. When thus positioned, these parts may be locked together by the bolts 10 as shown, thereby connecting together the dolly E, the collar F, the blocks G and the shaft attaching member H, in such manner as to permit longitudinal movement of the parts E, F and G with respect to the part H.

Centrally of the dolly E and in continuation of the aperture partly surrounded by the walls 20, is a downwardly extending cup member 22 provided in its lower wall with apertures 23. Thus cup member 22 affords an interior space for the member H when relative motion in one direction occurs between the dolly E and the member H. The extreme position of these parts in one direction is indicated in full lines in Figs. 1 and 3 and the changed position is indicated in dotted lines in Fig. 3.

A clothes engaging prong or finger 24 on the dolly E depends from each of the four corners and in the instance shown, each is made integral with the dolly. This is accomplished by forming the prong 24 into a hollow, tubular, somewhat conical shaped prong, slightly smaller at its lower end than at its top and suitably rounded so as not to tear the articles with which it may come in contact. It is provided at its lower end with an aperture 25. The edges of the dolly E are suitably rounded, as shown at 26.

In operation, a suitable mechanism imparts alternate rotary motion in opposite directions to the shaft B and consequently to the dolly E, which is connected thereto as stated, and causes the garments within the tub A to be engaged by the prongs or fingers 24 and swung alternately in one direction and then the other through the wash water, until the clothes are properly cleansed.

In order that the clothes may not be torn by the rotary, reciprocating action of the dolly, when the former accumulate in a mass, provision has been made for relieving the strain by providing for the upward movement of the dolly E as a whole. This is accomplished by the mechanism which provides relative motion between the dolly E and the shaft holding member H, in the manner hereinbefore stated, the dolly E falling down and hanging upon the button 5 by gravity as soon as the cause requiring its upward movement is removed,—such as a tangled mass of clothes.

In order that this relative motion between the parts may be the more readily accomplished, and in order to permit the proper circulation of the water in the tub, I have provided that the fingers 24 shall be hollow and have the apertures 25 at their lower ends. I have also provided the apertures 23 for the passage of any water which may seep into the interior of the cup shaped recess 22 as will be the case, because the connecting member H does not have a close fit in the bearing blocks G. Without the apertures 23 there would be too much suction and water friction. With the apertures 23 there is a tendency to a piston action of the button 5 within the cup 22 which tends to force the water out of the latter through the opening 23 and tends to create proper circulation of the water in the tub.

It will be observed that the agitator above described is made entirely of metal, the parts are so shaped that they may be readily formed by stamping or casting, and therefore fabricated at the minimum of cost. It will also be noted that the shape of the various parts is such that they may be readily put together by unskilled labor and therefore the cost of producing the device as a whole is very much reduced.

I claim as my invention:

1. As a new article of manufacture, a metal agitator for washing machines and the like, comprising a substantially square shaped flat disc member having a depending cylindrical hollow finger at each corner and means for attaching the agitator to an operating element.
2. As a new article of manufacture, a metal agitator for washing machines and the like, comprising a substantially square shaped flat disc member having a depending cylindrical hollow finger at each corner, each of said fingers being open at its top and bottom, and means for attaching the agitator to an operating element.
3. As a new article of manufacture, an all metal agitator for washing machines and the like, comprising a substantially square flat plate having hollow, apertured depending fingers, one in each corner, a central depending cup open at its top, a cap member to cover said opening, bearing blocks within the cap member and an attaching member projecting through and having longitudinal movement with respect to said bearing blocks.
4. As a new article of manufacture, an all metal agitator for washing machines and the like, comprising a substantially square flat plate having hollow, apertured depending fingers, one in each corner, a central depending cup open at its top and having an aperture through its bottom, a cap member to cover said open top, bearing blocks within the cap member and an attaching member projecting through and having longitudinal movement with respect to said bearing blocks.
5. As a new article of manufacture, an all metal agitator for washing machines and the like, comprising a substantially square flat plate having hollow, apertured depending fingers, one in each corner, a central depending cup open at its top and having an aperture through its bottom, a removable cap member to cover said open top, bearing blocks within the cap member and an attaching member projecting through and having longitudinal movement with respect to said bearing blocks.
6. An agitator for washing machines and the like, comprising a substantially flat square plate having a hollow apertured clothes engaging finger depending from each corner thereof and a central depending cup open at its top, combined with a cap member and means for removably securing same to the
- plate to cover said central opening, said cap member being provided with an apertured top, a pair of bearing blocks partially filling said aperture and provided with laterally extending flanges to hold said blocks in said cap, and an attaching member partially within the cup and cap members and having longitudinal movement through the bearing blocks.
7. An agitator for washing machines and the like, comprising a substantially flat square plate having a hollow apertured clothes engaging finger depending from each corner thereof and a central depending cup open at its top, combined with a cap member and means for removably securing same to the plate to cover said central opening, said cap member being provided with an apertured top, a pair of bearing blocks partially filling said aperture and provided with laterally extending flanges to hold said blocks in said cap, and an attaching member partially within the cup and cap members and having longitudinal movement through the bearing blocks, and means on the attaching member to engage the inner faces of the said blocks to limit said movement in one direction.
8. An agitator for washing machines and the like, comprising a substantially flat square plate having a hollow apertured clothes engaging finger depending from each corner thereof and a central depending cup open at its top, combined with a cap member and means for removably securing same to the plate to cover said central opening, said cap member being provided with an apertured top, a pair of bearing blocks partially filling said aperture and provided with laterally extending flanges to hold said blocks in said cap, and an attaching member partially within the cup and cap members and having longitudinal movement through the bearing blocks, an annular, outwardly projecting flange or button on the lower end of the attaching member adapted to limit the longitudinal movement thereof in one direction, and means for securing said attaching member to an operating element.

In testimony that I claim the foregoing as my invention I affix my signature, in the presence of two witnesses.

GLENN MORE.
